BOARD GAME APPARATUS

Emma E. Kloss, Chicago, Ill.

Application May 10, 1950, Serial No. 161,063

17 Claims. (Cl. 273—134)

1

The present invention relates in general to games, and has more particular reference to new and improved game apparatus affording opportunities for the playing of games incorporating novel combinations on which to base scoring or other game determinants.

An important object of the invention is to provide game elements including a deck of cards, a set of dice, a game board and a set of men for movement on the board, the game elements being inter-related as by means of indicia and color marking formed thereon; a further object being to provide a multiple suit deck of cards wherein corresponding card groups of the several suits are cross indexed, as by means of color markings; and a still further object being to provide a set of dice correlated with the several suits of the card deck and also with said cross indexed card groups; yet another object being to provide a game board correlated with the several suits of the card deck and also with the cross indexed card groups thereof.

Another important object is to provide a game board having a track for movable game pieces or men including adjustable means for determining playing conditions along the track.

Another important object is to provide game apparatus including cards, dice and game board wherein the movement of game pieces on the board may be determined by the drawing of cards in conjunction with the throw of dice; a further object being to provide game apparatus whereby the game may be scored in terms of movement of game pieces on a board in conjunction with the value of cards drawn or otherwise distributed from a card deck.

Another object is to provide game apparatus adapted for use in playing the novel game or games made possible by the foregoing novelties and improved features of the game apparatus as well as many conventional card, dice and other games; a further object being to provide apparatus whereby games based upon astrological lore may be played.

The foregoing and numerous other important objects, advantages and inherent functions of the invention will become apparent as the same is more fully understood from the following description which, taken in connection with the accompanying drawings, discloses a preferred embodiment of the invention.

Referring to the drawings:

Figure 1 illustrates cards comprising one complete twelve card suit of an eight suit card deck embodying the invention;

2

Figure 2 illustrates the ace cards of the eight suits of the complete deck;

Figure 3 illustrates eight extra or wild cards, one for each of the eight card suits;

Figures 4 and 5 illustrate additional wild or joker cards respectively designated "Milky Way" and "Comet";

Figure 6 is a face or plan view of a game board embodying the present invention;

Figures 6A, 6B, 6C and 6D respectively are enlarged views of successive sections of the endless track forming a part of the device shown in Figure 6;

Figure 7 is a sectional view taken substantially on the line 7—7 in Figure 6;

Figure 8 is a side view of playing pieces or men;

Figures 9, 10, 11, 12, 13, 14 and 15 respectively are developed views of the faces of dice embodying the invention; and

Figure 16 is a perspective view of a die containing the face markings shown in Figure 9.

To illustrate the invention the drawings show playing cards, dice, a game board and playing pieces or men, the cards being shown in Figs. 1—5; the dice in Figs. 9—16; the game board in Figs. 6 and 7; and the men in Fig. 8. In this connection the invention contemplates a deck of cards comprising eight suits of twelve cards each. The cards of each suit are preferably numbered in sequence from one to twelve, as shown in Fig. 1, in which the twelve numbered cards of a suit are illustrated; the card value numbers being preferably disposed in diagonally opposed corners of the cards. If desired, the twelve cards of each suit, in addition to or in place of the numbers, may be marked respectively with the twelve signs of the Zodiac and the calendar periods corresponding to such signs, to wit: Aries, the ram, March 21—April 19; Taurus, the bull, April 19—May 20; Gemini, the twins, May 20—June 21; Cancer, the crab, June 21—July 22; Leo, the lion, July 22—August 22; Virgo, the virgin, August 22—September 23; Libra, the scales, September 23—October 23; Scorpio, the scorpion, October 23—November 22; Sagittarius, the archer, November 22—December 21; Capricorn, the goat, December 21—January 20; Aquarius, the waterman, January 20—February 19; and Pisces, the fishes, February 19—March 21.

The cards of the several suits also may be distinguished by suit indicia, preferably in the form of colored suit spots in the diagonal corners of the cards, around the card value numbers, as shown in Fig. 2, which illustrates correspond-

cards of the several suits. If desired, the several suits may be named for astrological designations and marked accordingly with the names or symbols of said designations. Thus, the eight suits may be respectively called Sun, Moon, Mars, Mercury, Jupiter, Venus, Saturn and Wild Sky suits; and the suit identifying spots may respectively and correspondingly comprise yellow, blue, red, purple, green, brown, white circle and white square, respectively identified in the drawings by the reference numerals 21, 22, 23, 24, 25, 26, 27 and 28.

The cards of the several suits are also cross-indexed in groups as by means of suitable indicia preferably in the form of a band or bands of color in the body of the card. These preferably diagonally disposed color bands on the faces of the cards may represent the elements Fire, Earth, Air and Water corresponding with and represented by color bands of red, green, yellow and blue, designated respectively in the drawings by reference numerals 29, 30, 31 and 32, the red index bands 29 being applied on the one, five and nine cards of each suit; the green bands 30 being applied on the two, six and ten cards; the yellow bands 31 being applied to the three, seven and eleven cards; and the blue bands 32 being applied to the four, eight and twelve cards of each suit.

Preferably the colors red, green, yellow and blue of the cross index bands 29, 30, 31 and 32 are of darker color shades than the colors applied in the red, green, yellow and blue suit spots 23, 25, 21 and 22. The color bands 29, 30, 31 and 32 are preferably applied as parallel spaced bands across the card in preferably diagonal fashion; and the space between the said parallel bands may be used for the display therein of appropriate astrological or other matter, as for example, game score bonus or penalty directives.

In addition to the twelve numbered or otherwise identified cards thereof, each suit may include an additional preferably un-numbered card, as shown in Fig. 3. These cards may be regarded as a wild suit card; or each may be used as the "King" card of its corresponding suit, when using the cards of any four of the suits for playing any conventional card game. The medial portions of these additional suit cards may be used for the display of astrological or other matter, as for example, game score bonus or penalty directives.

A pair of wild or joker cards 34 and 35 respectively designated "Milky Way" and "Comet" may also be provided as shown in Figures 4 and 5.

The card deck thus comprises a total of one hundred and six cards, which if desired may be used as two separate conventional card decks of fifty-two cards and a joker each; or the cards may be employed in novel fashion hereinafter indicated and described in playing entirely new games.

In this connection the present invention contemplates the use of a novel game board, shown in Figures 6 and 7 in conjunction with the improved card deck for game purposes. To this end, the game board comprises a base panel 36 of preferably rectangular configuration and a preferably circular disc 37 pivoted for turning movement on and above the base panel. Outwardly of the marginal edge of the disc 37, the base panel is formed with a preferably circular endless playing track or course 38 divided into three hundred and sixty-six segments 39 which may represent the days of the calendar year.

These segments may be subdivided in groups to form consecutive sections of the track which may be identified by the names of the calendar months, to wit: the January section, 41; the February section, 42; the March section, 43; the April section, 44; the May section, 45; the June section, 46; the July section, 47; the August section, 48; the September section, 49; the October section, 50; the November section, 51; the December section, 52. The width of the segments 39 is preferably adjusted so that the sections 41-52 are of equal length, although this is not essential. It will be noted, however, that each segment 39 corresponds with a particular day of the year, the segment corresponding with February 29, leap year day, being preferably marked to distinguish it from the remaining sections.

The disc 37 also is divided into seven segments 61, 62, 63, 64, 65, 66 and 67 as by means of radial lines 53 marked thereon. Each of the segments is preferably colored in accordance with the suit identifying color spots of the card suits 21-28, that is to say, the Sun, Moon, Mars, Mercury, Jupiter, Venus and Saturn card suits. If desired, a representation of the fanned cards of each suit may be formed, as shown, in the appropriate corresponding sections of the game board. It will be noted that the Wild Sky suit 28 is not represented upon the turnable dial portion 37 of the game board. A replica of the cards of the Wild Sky suit, however, may be formed on the board 36, preferably in the corners of the board, wherein portions of the cards of said Wild Sky suit 28 are arranged in fanned relationship in groups of three card replicas in each of the four corners of the board, in accordance with the cross-indexing color strips 29, 30, 31 and 32 of said Wild Sky suit. As shown, a replica of portions of the three red striped cards 1, 5 and 9, namely the fire cards of the suit, may be arranged at station 54 in the lower right-hand corner of the board, viewing Fig. 6. A replica of the earth cards of said suit, numbered 2, 6 and 10, identified by green color stripes may be disposed at a station 55 in the lower left-hand corner of the board. A replica of the air cards of said suit, numbered 3, 7 and 11, and identified by yellow stripes may be disposed at a station 56 in the upper left-hand corner of the board. A replica of the water cards of said suit, numbered 4, 8 and 12, and identified by blue stripes, may be disposed at a station 57 at the upper right-hand corner of the board.

In addition, the board may also contain replicas 58 and 59 respectively of the "Milky Way" and "Comet" cards 34 and 35.

The present invention further contemplates the embodiment of playing pieces or men which may be formed as illustrated in Figure 8, there being a total of seven playing pieces provided, each distinguishable from the others by suitable marking. To this end the playing pieces may have portions thereof distinctively colored to correlate each piece with its corresponding game board section and card suit. As shown, the playing piece 71 may be colored yellow to correspond with the board segment 61 and with the Sun playing suit 21. The pieces 72, 73, 74, 75, 76 and 77 likewise may respectively be colored blue, red, purple, green, brown and white to correspond with the board segments 62-67, and with the Moon, Mars, Mercury, Jupiter, Venus and Saturn suits 22-27. These playing pieces may be used, as hereinafter more fully described, as travelling

markers on the graduated board track or course

38. The present invention also provides a novel set of dice marked and colored to correlate the same with the playing cards heretofore described.

In this connection the dice set preferably comprises seven dice having face arrangements respectively illustrated in Figures 9-15 of the drawings, Figure 16 illustrating the die corresponding with the Figure 9 face arrangement showing 10. The die 81 illustrated in Figures 9 and 16 has a pair of opposite faces formed with identifying color spots 91 matching the yellow suit color of the Sun suit 21. The dice 82, 83, 84, 85, 86 and 87, illustrated in Figs. 10-15, each have a pair of opposite faces bearing identifying spots 92-97 respectively colored blue, red, purple, green, brown and white to match said dice respectively with the Moon, Mars, Mercury, Jupiter, Venus and Saturn suits 22-27.

The remaining four faces 99, 100, 101 and 102 of the dice 81-86 bear numerals and are colored respectively red, green, yellow and blue so that each die has a face colored in accordance with the four cross-indexing color bands 29, 30, 31 and 32. Two of the dice, namely the dice 81 and 84, respectively carrying the yellow and purple suit identifying spots 91 and 94 have their facets 99, 100, 101 and 102 marked respectively with the numerals 1, 6, 7 and 12. The dice 82 and 85 respectively carrying blue and green suit identifying spots 92 and 95 have their facets 99, 100, 101 and 102 marked respectively with the numerals 5, 2, 11 and 8. The dice 83 and 86 respectively carrying red and brown suit identifying spots 93 and 96 have their facets 99, 100, 101 and 102 marked respectively with the numerals 9, 10, 3 and 4. It will be seen that the numerals carried by each die add up to a total of 26. It will be seen also that the red facets 99 of the dice group comprising the dice 81, 82 and 83 contain the numerals 1, 5, and 9 which are the identifying numbers of the suit cards carrying the red cross-indexing bands 29; the green facets 100 contain the numerals 6, 2 and 10 corresponding with the identifying numbers of the suit cards carrying the green indexing stripes 30; the yellow facets 101 contain the numerals 7, 11 and 3 corresponding with the identifying numbers of the suit cards carrying the yellow cross-indexing bands 31; and the blue facets 102 contain the numerals 12, 8 and 4 corresponding with the identifying numbers of the suit cards carrying the blue cross-indexing bands 32. The colored facets of the dice 84, 85 and 86 embody the identical arrangement of identifying numerals therein.

The remaining die 87, shown in Fig. 15, has four facets 103, 104, 105 and 106 labeled respectively with the notations "Stop", "Comet" corresponding with the wild or joker card 35; "Wild Sky" corresponding with the Wild Sky card suit 28; and "Milky Way" corresponding with the wild or joker card 34.

It will be seen from the foregoing that the playing cards, the dice, the playing pieces and the game board are all interrelated by cross-indexing markings comprising the card suit markings, the card value markings and the cross-indexing markings so that a multiplicity of chance determining relationships are thereby incorporated for utilization in games played with the above described equipment. Playing rules for many different games and game variants will suggest themselves whereby the multiple chance determining possibilities of the present invention

may be utilized, for example, by throwing the dice, innumerable combinations of rules across indexing colors and suit colors may be obtained for controlling the draw of cards in succession from the shuffled card deck, or for determining the advancement of playing pieces on the track 38. Since the dice are marked with reference to the marking of the cards, it is obvious that many chance determinants for the drawing and playing of cards may be obtained by casting the dice. Furthermore, the interrelated markings of dice and cards, being also related to the marking of other playing pieces and the marking of the board segments allow multifarious chance determination for controlling the advancement of the playing pieces on the track 38 in accordance with piece movement determined either by throwing the dice or by drawing cards, or by combination card draw and dice throw.

An important aspect of the present invention, furthermore, resides in the provision for adjusting the disc 37 and its cross-referenced segments with respect to the playing track 38. By adjusting the disc 37 either arbitrarily or in accordance with set rules, the various segments may be disposed in position registering with portions of the playing track to thereby determine movement of correspondingly referenced playing pieces in such track zones. More particularly, in this connection, the travel of a playing piece along the track 38 may be facilitated, by suitable game rule, in that portion of the track opposite a disc segment of color corresponding to the playing piece, and may be made more difficult during travel of the piece opposite other disc segments.

In order to illustrate game possibilities, the following rules may be adopted for the playing of a specific game.

The players, up to seven in number, take places around the board. The players serve in succession as dealer.

The dial pointer is set on the track to the graduation corresponding with the birth date of the dealer, thus adjusting the dial segments opposite corresponding sections of the track. Each player is assigned the suit color of the dial segment nearest to the player, who uses the correspondingly colored playing piece or man. The playing pieces or men are placed in starting position on the track each at the graduation corresponding with the respective birth date of the player to which the piece has been assigned.

The cards are then well shuffled and cut, and the dealer then distributes one card in turn to each player, and places the balance of the card pack, face down, in the circle at the center of the dial. Thereafter each player, starting with the dealer, performs the following acts: (1) draws one card from the top of the card pack or from the discard pile; (2) throws the dice; (3) moves the player's playing piece, as indicated by the card draw and dice throw; and (4) optionally discards one card upon the discard pile next to the card pack.

If the player in the initial deal, or by subsequent draw from the card pack or discard, obtains a card of suit color matching the disc segment registered with the track section in which the player's man is then disposed, the man is immediately advanced a stated number of day graduations on the track. Such advance may be the number of graduations equal to the numerical face value of the drawn or dealt card, or an arbitrary number of graduations, as fifteen if the

card be a wild suit card, or twenty if the card be either of the joker cards 34 and 35.

The playing piece may also be advanced in accordance with the dice throw, providing the throw shows either the player's suit color, or the suit color of the disc segment opposite which the player's man is then disposed on the track, otherwise not. If the player's suit color is thrown, however, the playing piece may be advanced on the track a number of graduations equal to the largest total of dice digits thrown having the same cross-index color. If such color corresponds with the cross index color band of the card drawn by the player immediately before the dice throw, the digit total may be doubled and the player's piece advanced accordingly.

In the event that the dice throw shows the "Stop" facet of the "Wild" die, the dice throw score is cancelled and the piece may not be moved unless the player's piece is located in the track section opposite the disc segment bearing the player's suit color, in which event the throw of the "Stop" facet is ineffective to cancel the dice throw score.

A throw of dice showing either the "Comet" or the "Milky Way" die facet may be made to increase the dice throw score, as by doubling the same, if the player's piece is in a track zone opposite a stated disc segment, such as the yellow segment. Should the "Wild Sky" facet show in a dice throw the score may be increased, as by three times or other arbitrarily set bonus. Numerous other bonus or penalty conditions may be set by agreement or rule based on the interrelation of numeral, color, and "Wild" markings on the cards, dice and the adjustable disc of the playing board, as will be apparent.

The object of the game may be the completion of the circuit of the track and the collection in hand of as many cards of the player's suit as possible, and the collection of cards of the "Wild Sky" card suit, in cross-indexed sets of three. In this connection the game may be made to end when one player completes the circuit of the track, or may be allowed to continue until all have completed the circuit. Alternately the game may be made to end when at least one player has completed a circuit of the track and a player has completed the collection of a complete suit.

In collecting suit cards, the "Comet" and "Milky Way" cards may be substituted for any card in the deck. The extra unnumbered suit cards may be used each as substitute for any numbered card of its suit. The cards of the Wild Sky suit may be substituted only for the corresponding cards of any other suit.

Game score points may be awarded on any desired or selected basis. For example, points might be awarded as follows:

100 points to first player to complete the track circuit.

50 points to next player to complete the track circuit.

25 points to third player to complete the track circuit.

150 points to player first collecting complete suit, without wild cards or other substitutes.

100 points to other players collecting complete suits without wild cards or other substitutes.

50 points to all players collecting suits completed with aid of wild or substitute cards.

30 points for each triplet set of Wild Sky suit cards.

From the foregoing, it will be seen that the novel cross matching or indexing of the cards, dice, playing board and playing men, as by means of color and numerical indicia, in accordance with the present invention, affords great chance flexibility in the assignment of playing penalties and bonuses, and in otherwise affecting playing conditions. These improvements are afforded not only by the provision of an adjustable board whereby to regulate the playing conditions along the track, but also by the cross indexing, as by numeral indicia and color, of the cards with the dice, as well as by the matching, as by color, of the playing pieces and the track adjusting disc segments with the card suits and dice.

It is thought that the invention and its numerous attendant advantages will be understood from the foregoing description, and it is obvious that numerous changes may be made in the form, construction and arrangement of the several parts without departing from the scope or spirit of the invention, or sacrificing any of its attendant advantages, the form herein disclosed being a selected embodiment for the purpose of illustrating the invention.

The invention is hereby claimed as follows:

1. Game apparatus comprising a board having a circular track graduated in steps representing the days of the calendar year, a disc turnably mounted on said board in position within and with its peripheral edge in registration with said track, said disc at and inwardly of its edge being marked to define seven segments, forming play controlling zones, adjustable around the circular track by turning the disc on the board, differentiated playing pieces marked to correspond each with a matching one of said segments and movable around the circular track in moves determined by the chance drawing of cards and throwing of dice, as modified by the adjustment of said disc, a pack of cards comprising a plurality of thirteen-card suits each marked to correspond with a matching one of said segments of the disc, an additional wild suit and a pair of joker cards, the cards of the several suits of said pack being cross indexed by color markings to correlate the same in sets comprising the first, fifth and ninth cards; the second, sixth and tenth cards; the third, seventh and eleventh cards; and the fourth, eighth and twelfth cards of the several suits, a set of seven dice, each die of said set having a pair of opposed faces marked to correspond with a matching one of said segments, at least one of said dice having its remaining four faces marked to correspond respectively with said additional wild suit, said joker cards and a stop symbol, the remaining dice having their remaining four faces marked with number symbols, in the range, between and including one and twelve and so arranged that the numbers represented on the faces of each of said dice total twenty-six, said number symbol carrying faces being also colored in conformity with the cross indexing colors of said cards.

2. Game apparatus comprising a board having a circular track graduated in steps representing the days of the calendar year, a disc turnably mounted on said board in position within and with its peripheral edge in registration with said track, said disc at and inwardly of its edge being marked to define a plurality of segments, forming play controlling zones adjustable around the circular track by turning the disc on the board, a plurality of differentiated playing pieces movable around the circular track in moves determined

by the chance drawing of cards and throwing of dice, as modified by the adjustment of said disc, a pack of cards comprising a plurality of card suits each marked to correspond with a matching one of said segments of the disc, an additional wild suit and a pair of joker cards, a set of seven dice, each die of said set having a pair of opposed faces marked to correspond with a matching one of said segments, at least one of said dice having its remaining four faces marked to correspond respectively with said additional wild suit, said joker cards and a stop symbol, the remaining dice having their remaining four faces marked with number symbols, in the range, between and including one and twelve.

3. Game apparatus comprising a board having a circular track graduated in steps, a disc turnably mounted on said board in position within and with its peripheral edge in registration with said track, said disc at and inwardly of its edge being marked to define a plurality of segments, forming play controlling zones adjustable around the circular track by turning the disc on the board, a plurality of differentiated playing pieces movable around the circular track in moves determined by the chance throwing of dice, as modified by the adjustment of said disc, a set of dice, each die of said set having a pair of opposed faces marked to correspond with a matching one of said playing pieces, at least one of said dice having its remaining four faces marked with game controlling wild symbols, the remaining dice having their remaining four faces marked with number symbols, in the range, between and including one and twelve and so arranged that the numbers represented on the faces of each of said dice total twenty-six.

4. Game apparatus comprising a board having a circular track graduated in steps, a disc turnably mounted on said board in position within and with its peripheral edge in registration with said track, said disc at and inwardly of its edge being marked to define a plurality of segments, forming play controlling zones, adjustable around the circular track by turning the disc on the board, a plurality of differentiated playing pieces movable around the circular track in moves determined by the chance drawing of cards as modified by the adjustment of said disc, a pack of cards embodying a plurality of suits each correlated with a corresponding one of said playing pieces, an additional wild suit and a pair of joker cards.

5. Game apparatus comprising a board having a circular track graduated in steps, a disc turnably mounted on said board in position within and with its peripheral edge in registration with said track, said disc at and inwardly of its edge being marked to define a plurality of segments, forming play controlling zones, adjustable around the circular track by turning the disc on the board, a plurality of differentiated playing pieces marked to correspond each with a matching one of said segments and adapted to travel around the circular track in moves determined by chance, as modified by the adjustment of said disc.

6. Game apparatus comprising a pack of cards embodying a plurality of suits and a pair of joker cards, the cards of the several suits of said pack being cross-indexed by color markings to correlate the same in sets comprising the first, fifth and ninth cards; the second, sixth and tenth cards; the third, seventh and eleventh cards; and the fourth, eighth and twelfth cards of the several suits and a set of seven dice, each

die of said set having a pair of opposed faces marked to correspond with a matching one of said suits, at least one of said dice having its remaining four faces marked with game controlling wild symbols, the remaining dice having their remaining four faces marked with number symbols, in the range, between and including one and twelve and corresponding with the cross indexed number sets of said card pack, said numbers being so arranged that the numbers represented on the faces of each of said dice total twenty-six, said number symbol carrying faces being also colored in conformity with the cross indexing colors in said cards.

15 7. Game apparatus comprising a pack of cards embodying seven thirteen-card suits corresponding with each of said segments of the dice, an additional thirteen-card wild suit and a pair of joker cards, the cards of the several suits of said pack being cross-indexed by color markings to correlate the same in sets comprising the first, fifth and ninth cards; the second, sixth and tenth cards; the third, seventh and eleventh cards; and the fourth, eighth and twelfth cards of said several suits, a set of seven dice, each die of said set having a pair of opposed faces marked to correspond with a matching one of said seven suits, at least one of said dice having its remaining four faces marked to correspond respectively with said additional wild suit, said joker cards and a stop symbol, the remaining dice having their remaining four faces marked with symbols, and colored in conformity with the cross indexing colors in said cards.

35 8. A set of dice, for game playing purposes, in conjunction with a pack of cards in which individual card elements are mutually interdistinguishable by cross indexing the same with interdistinguishable colors, each die of said set having a pair of opposed faces formed with an individual die distinguishing marking, at least one die of said set having its remaining four faces marked to correspond respectively with game controlling wild indicia, the remaining dice having their remaining four faces marked with symbols, and colored in conformity with the cross indexing colors in said cards.

19 9. A set of dice, for game playing purposes, in conjunction with a pack of cards in which individual card elements are mutually interdistinguishable by cross indexing the same with interdistinguishable colors, each die of said set having a pair of opposed faces marked with a die distinguishing color, at least one die of said set having its remaining four faces marked to correspond respectively with game controlling wild indicia, the remaining dice having their remaining four faces marked with number symbols, in the range between and including one and twelve and so arranged that the numbers represented on the faces of each of said dice total twenty-six, said number symbol carrying faces being also colored in conformity with the cross indexing colors in said cards.

65 10. A set of dice, each die of said set having a pair of opposed faces marked with a die distinguishing color, at least one of said dice having its remaining four faces marked respectively with the numbers one, six, seven and twelve, another of said dice having its remaining four faces marked respectively with the numbers two, five, eleven and eight, and another of said dice having its remaining four faces marked respectively with the numbers three, four, nine and ten whereby the numbers represented on the faces

11

of each of said dice total twenty-six, said number carrying faces being also contrastingly colored to cross index said numbers in numeral sets comprising one, five and nine; two, six and ten; three, seven and eleven; and four, eight and twelve.

11. A set of dice, each die of said set having a pair of opposed faces marked with a die distinguishing color, at least one of said dice having its remaining four faces marked respectively with the numbers one, six, seven and twelve, another of said dice having its remaining four faces marked respectively with the numbers two, five, eleven and eight, and another of said dice having its remaining four faces marked respectively with the numbers three, four, nine and ten, the faces marked one, five and nine being colored red, those marked two, six and ten being colored green, those marked three, seven and eleven being colored yellow, and those faces marked four, eight and twelve being colored blue.

12. Game apparatus comprising a board having a circular track graduated in steps, a disc turnably mounted on said board in position within and with its peripheral edge in registration with said track, said disc at its edge being marked to define a plurality of segments, forming play controlling zones, adjustable around the circular track by turning the disc on the board, and a set of dice, each die of said set having a pair of opposed faces formed with an individual die distinguishing marking to correlate each die with a corresponding segment of the board, at least one die of said set having its remaining four faces marked with game controlling wild indicia, the remaining dice of the set having their remaining four faces marked with number symbols for the chance determination of playing conditions on the circular track of the board.

13. Game apparatus comprising a board having a circular track graduated in steps, a disc turnably mounted on said board in position within and having its peripheral edge in registration with said track, said disc at its edge being marked to define a plurality of segments, forming play controlling zones adjustable around the circular track by turning the disc on the board, and a pack of playing cards marked to identify the individual cards in sets and to correlate each set with a corresponding one of said segments of the disc.

14. Game apparatus comprising a board having a circular track graduated in steps, a disc turnably mounted on said board in position within and having its peripheral edge in registration with said track, said disc at its edge being marked to define a plurality of segments, forming play controlling zones, adjustable around the circular track by turning the disc on the board, a pack of playing cards marked to identify the individual cards in sets and to correlate each set with a corresponding one of said segments of the disc, and a set of dice, each die of said set having a pair of opposed faces formed with an individual die distinguishing marking to correlate each die with a corresponding segment of the disc, at least one die of said set having its remaining four faces marked with game controlling wild indicia, the remaining dice of the set having their remaining four faces marked with symbols for the chance determination of playing conditions on the circular track of the board.

15. Game apparatus comprising a board having a circular track graduated in steps, a disc turnably mounted on said board in position

12

within and with its peripheral edge in registration with said track, said disc at its edge being marked to define a plurality of segments, forming play controlling zones, adjustable around the circular track by turning the disc on the board, a set of dice, each die of said set having a pair of opposed faces formed with an individual die distinguishing marking to correlate each die with a corresponding segment of the disc, at least one die of said set having its remaining four faces marked with game controlling wild indicia, the remaining dice of the set having their remaining four faces marked with symbols for the chance determination of playing conditions on the circular track of the board, and a set of playing pieces or men each marked to correlate the same with a corresponding segment of the board.

16. Game apparatus comprising a board having a circular track graduated in steps, a disc turnably mounted on said board in position within and having its peripheral edge in registration with said track, said disc at its edge being marked to define a plurality of segments, forming play controlling zones, adjustable around the circular track by turning the disc on the board, a pack of playing cards marked to identify the individual cards in sets and to correlate each set with a corresponding one of said segments of the disc, and a set of playing pieces or men each marked to correlate the same with a corresponding segment of the disc.

17. Game apparatus comprising a board having a circular track graduated in steps, a disc turnably mounted on said board in position within and having its peripheral edge in registration with said track, said disc at its edge being marked to define a plurality of segments, forming play controlling zones adjustable around the circular track by turning the disc on the board, a pack of playing cards marked to identify the individual cards in sets and to correlate each set with a corresponding one of said segments of the disc, and a set of dice, each die of said set having a pair of opposed faces formed with an individual die distinguishing marking to correlate each die with a corresponding segment of the disc, at least one die of said set having its remaining four faces marked with game controlling wild indicia, the remaining dice of the set having their remaining four faces marked with symbols for the chance determination of playing conditions on the circular track of the board, and a set of playing pieces or men each marked to correlate the same with a corresponding segment of the disc.

55 EMMA E. KLOSS.
